2 SHEETS—SHEET 2.

UNITED STATES PATENT OFFICE.

SAMUEL FARRIS BASHARA, OF HOUSTON, TEXAS.

AUTOMATIC SIGNAL-ACTUATING MECHANISM FOR RAILWAYS.

1,346,934.

Specification of Letters Patent. Patented July 20, 1920.

Application filed March 15, 1918. Serial No. 222,728.

To all whom it may concern:

Be it known that I, SAMUEL F. BASHARA, a citizen of the United States, residing at Houston, in the county of Harris and State 5 of Texas, have invented certain new and useful Improvements in Automatic Signal-Actuating Mechanism for Railways, of which the following is a specification, reference being had therein to the accompanying drawing.

My invention relates to automatic signal actuating mechanism for railways, and more specifically relates to improvements on the actuating mechanism disclosed by the patent to J. Fears of March 9, 1915, Serial No. 15 732,696. Further my invention relates to automatic signal operating mechanism which is actuated by the wheels of a car movable over a rail, and which mechanism is capable of being operated by the wheel from 20 any one of a number of points along the rail. The points of operation preferably extend along the rail at suitable intervals on both sides of the position where the signal proper is located, so that the car wheels 25 contacting with the operating mechanisms at intervals will cause the signal to be repeated a number of times before the train reaches the location of the signal. In the 30 present invention a flag is employed mounted upon a pivoted or swinging semaphore arm which, when actuated or oscillated repeatedly by the action of the car wheels at the several points of operation will cause 35 the flag to wave to attract attention thereto.

So that my invention may be more readily understood reference is made to the following detail description in connection with the accompanying drawings.

40 In the drawings:

Figure 1 is a top plan view of a railway track showing the arrangement of the signal operating mechanism.

Fig. 2 is a fragmentary side elevation of 45 the same.

Figs. 3 to 9 are detail views of the mechanism.

1 represents a section of a track. At suitable intervals along the track are positioned 50 hangers as shown at 2 in the drawings. These hangers are in the form of U-shaped or channel members which are located between the ties and which have laterally extending flanges 3 by which said members 55 are fastened to the ties and supported therefrom. 4 designates a top plate for the

members 2. These members or housings 2 are positioned immediately adjacent the rail and preferably abut against the same. Within each housing or member 2 is disposed an upstanding plunger 5 having oppositely inclined surfaces 6 at the head thereof. Upon these contact surfaces the wheels of the car act to force the plunger downward, the heads or contact surfaces 65 being positioned in close proximity to the rail and slightly above the upper head thereof. The plunger 5 preferably extends through the floor or base of the member 2 a suitable distance and through an opening 70 in the cover plate 4. Passing through a hole 7 in the plunger, near the head 6 thereof, is a laterally extending pin 8, and surrounding the plunger 5 and bearing against the base of the housing 2 and against 75 the pin 8 is a coiled spring 9. Said spring normally acts to maintain the plunger in elevated position when not engaged by the car wheel. On the opposite side of the rail from the housing 2 and in horizontal 80 alinement therewith is a plate 10 suitably secured to the same ties as the member 2. This plate 10 bridges or spans the ties, and on the inside thereof i. e. the side next to the rail, is a depending flange or plate 11 85 extending downwardly between the ties. An elongated vertical slot 12 is formed in the flange 11. Pivottally connected near one of the upper corners of the flange or plate 11 is a second plate 13. This plate 13 is 90 pivoted near one side edge thereof and has an open ended elongated slot 14 extending inwardly from one side edge thereof. Through the open ended slot 14 of the plate 13 and the slot 12 of the plate 11 extends 95 the pin 8 carried by the plunger 5, which pin passes through a suitable opening in the rail 1. Therefore it will be readily seen that the pin 8 being carried by the plunger 5 will move downwardly therewith 100 when said plunger is depressed by the car wheels and the other end of the pin 8 having engagement with the horizontal slot in the pivoted plate 13 will cause the plate 13 to rock about its pivot point and move relative 105 to the stationary plate 11.

The plate 13 has extending from the top thereof an upstanding ear or lug 15. This ear or lug 15 has pivotally connected thereto 110 an angle member or plate 16 which has two transversely extending flanges 17. The member 16 being pivotally connected with

the pivoted plate 13 is caused to move therewith.

Rigidly connected at the ends by suitable means to each flange 17 of the member 16 are relatively long bars 18, which extend along the side of and parallel to the tracks 1. These bars 18 are supported intermediate their ends at suitable intervals by guide brackets 19 fastened to the ties, and said 10 bars are interconnected by the tie plates 20 having upstanding flanges 21 to which the ends of the bars are rigidly fastened.

Pivottally fastened to the base of the member 20 is one arm of a bell crank lever 22, 15 which is pivoted at 23 to a suitable support as 24, preferably in the form of an extra tie. The other end of the lever 22 has pivottally fastened thereto a member 25 having a vertical flange 26 to which is rigidly secured another bar 27. This bar 27 extends across the track at right angles to the rail thereof, passing through or under the rails. The end of this rod 27 connects with an angle arm 28, which arm is pivottally connected to one arm of a bell crank lever 29, 20 the lever 29 being pivottally attached and carried by an up-standing signal post or support 30. The other arm of the lever 29 is pivottally connected to a connecting 25 plate 31 on the lower end of which is fastened a vertically extending rod 32. The rod 32 extends to within a short distance of the top of the post where it is connected to a semaphore arm 33 by an angle arm 34. 30 The semaphore arm 33 is supported at the top of the post 30 through suitable brackets 35 being pivottally connected to the post at 36, and carrying on its upper end a visual signal in the form of a flag or target 37. 35 Near the upper end of the post 30 is secured a bell 38, and connected to the lower end of the semaphore arm 33 is a hammer arm or striker 39 so fastened thereto that when the arm 33 is oscillated around its 40 pivot point the hammer 39 will contact with and sound said bell.

The operation of my signal operating mechanism will be readily understood. The 45 wheels of the car passing over the rail will contact with the head 6 of the plunger and depresses the same, whereby the pin 8 is depressed which in turn causes the plate 13 to tilt or rock around its pivot point. The movement of the plate 13 causes the bars 18 to reciprocate, which in turn rocks the bell crank lever 22 and this lever through its connecting rod operates the lever 29 to which the bar 32 is attached, and the bar 32 being connected with the semaphore arm oscillates 55 the same causing the signal at the end thereof to be waved, and also causing the hammer to sound the bell.

It is my intention to locate a plurality of these mechanisms along the track at suitable 60 intervals, and have them so intercon-

nected and spaced that the car wheels will actuate the mechanism successively and cause the semaphore arm to oscillate a number of times before the car reaches the location of the signal, thereby waving the flag 70 or visual signal, and also sounding the bell or audible signal a number of times before the location of the signal proper is reached.

I further contemplate placing upon the semaphore arm a light as at 40, so a visual 75 signal will be provided in the dark. This light is preferably electric and connected to a suitable source of power.

Having thus described my invention, what I claim is:

1. An automatic signal actuating mechanism comprising a housing supported from the tie by laterally extending flanges and located adjacent the rail, a spring pressed plunger adapted to be depressed and positioned within the housing, said plunger having a head with which the car wheels are adapted to contact, a laterally extending pin secured at one end to the plunger near the head thereof, the other end of the pin having engagement with a plate having an elongated vertical slot, a pivoted plate secured to the first mentioned plate, the pin engaging a horizontal slot in the pivot plate, and operable connections between the pivot plate and a pivoted signal arm. 80

2. An automatic signal actuating mechanism comprising a housing located adjacent the rail, a spring pressed upstanding plunger adapted to be depressed and positioned 100 within the housing and having a head adapted to be engaged by the wheels of a car, a laterally extending pin secured at one end of the plunger, the pin having engagement with a plate having a vertically extending slot, a second plate pivoted to the first mentioned plate, the second plate having an open ended horizontal slot extending from one side edge thereof, the pin having engagement with said slot, an upstanding flange formed integral with the top of the pivoted plate and operable connections between the same and a pivoted signal arm. 105

3. An automatic signal actuating mechanism comprising a housing located adjacent 115 the rail, a plunger positioned and adapted to be depressed within the housing, and having a head with which the car wheels are adapted to contact, a lateral projection on said plunger, the projection having engagement with a pivoted plate, a signal arm in the form of a bell crank lever, said arm being pivottally connected to an upstanding support, one end of the signal arm carrying a visual signal and the other end of 120 the arm carrying a striker arm adapted to contact with a bell positioned upon the upstanding support, and operable connections between the pivot plate and the signal arm comprising longitudinally reciprocating 125

bars interconnected with bell crank levers and a vertically extending bar pivotally connected with the signal arm.

4. An automatic signal actuating mechanism comprising a housing located adjacent the rail, a plunger positioned and adapted to be depressed within the housing and having a head with which the car wheels are adapted to contact, a laterally projecting pin on the plunger, a guide plate in which said pin is adapted to reciprocate vertically, a bell crank lever pivoted on said plate and having a horizontally arranged slot to receive said pin, said lever having operative connection with a signal arm.

5. An automatic signal actuating mechanism comprising a housing located adjacent the rail, a spring pressed plunger adapted

to be depressed within said housing, a head on said plunger having oppositely inclined contacting surfaces with which the car wheels are adapted to contact, a pin secured at one end to the plunger, the other end of the pin having a slideable engagement with a pivoted plate, said plate having a horizontal slot to receive said pin, said plate having a lever arm thereon and operable connections between said lever arm and a swinging signal arm.

In testimony whereof I hereunto affix my signature in the presence of two witnesses.

SAM FARRIS BASHARA.
